UNITED STATES PATENT OFFICE.

GEORGE AINSWORTH, OF GREAT NECK, NEW YORK, ASSIGNOR TO ALFRED VESTER & SONS, INC., OF PROVIDENCE, RHODE ISLAND, A CORPORATION.

DESIGN FOR A PENDULET.

Application filed April 26, 1923. Serial No. 5,967. Term of patent 7 years.

To all whom it may concern:

Be it known that I, GEORGE AINSWORTH, a citizen of the United States, and residing at Great Neck, in the county of Nassau and State of New York, have invented a new, original, and ornamental Design for Pendulets, of which the following is a specification, reference being had to the accompanying drawing, forming part thereof.

The figure is a perspective view of a pendulet, showing my new design.

I claim:

The ornamental design for a pendulet, as shown.

GEORGE AINSWORTH.
